CLAIM

The ornamental design for a radio transmitter or receiver which is connectable to a computer or a portable music device, as shown and described.

DESCRIPTION

FIG. 1 is a perspective view of an embodiment of a radio transmitter or receiver showing our new design; FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view similar to that of FIG. 1 but showing in dotted lines a computer which is capable of being connected to the radio transmitter or receiver;

FIG. 9 is a perspective view of an alternative embodiment of a radio transmitter or receiver showing our new design;

FIG. 10 is a front view thereof, the back view thereof being identical to the FIG. 3 view;

FIG. 11 is a left side view thereof, the right side view being a mirror image;

FIG. 12 is a top view thereof, the bottom view thereof being identical to the FIG. 7 view;

FIG. 13 is a perspective view of another alternative embodiment of a radio transmitter or receiver showing our new design;

FIG. 14 is a front view thereof, the back view thereof being identical to the FIG. 3 view;

FIG. 15 is a left side view thereof, the right side view being a mirror image;

FIG. 16 is a top view thereof, the bottom view thereof being identical to the FIG. 7 view;

FIG. 17 is a perspective view of yet another alternative embodiment of a radio transmitter or receiver showing our new design;

FIG. 18 is a front view thereof, the back view thereof being identical to the FIG. 3 view;

FIG. 19 is a left side view thereof, the right side view being a mirror image; and,

FIG. 20 is a top view thereof, the bottom view thereof being identical to the FIG. 7 view.

The broken lines shown in the drawings form no part of the claimed design.
